UNITED STATES PATENT OFFICE.

HENRY BREHMER, OF STAPLETON, ASSIGNOR TO DAVID WOLFE BRUCE, OF NEW YORK, N. Y.

DESIGN FOR TYPE.

SPECIFICATION forming part of Design No. 15,749, dated January 27, 1885.

Application filed December 13, 1884. Term of patent 14 years.

To all whom it may concern:

Be it known that I, HENRY BREHMER, (assignor to DAVID WOLFE BRUCE,) of Stapleton, county of Richmond, and State of New York, have invented a new Design for a Font of Printing-Type, of which the following is a specification.

The nature of my design is clearly shown in the accompanying typographic impression, to 10 which reference is made; and it consists of a letter of the class known as "modern antique," ornamented about centrally, with the exception of the letters G and L, by light curved lines, with heavy dot termination placed upon 15 each side of the up and down portions of the letters. In the G and L this curved line, with heavy dot termination, is found upon the left of the up and down portion. The faces of the letters are further ornamented by a series of

curved lines with dot termination, tendril-like ornaments, and spear-head-like ornaments, and reference is made to the typographic impression, which shows them fully.

The character of the design proper is found in the symbol "and," the exclamation-point, 25 the interrogation-point, the numerals 1 2 3 4 6 7 8 9 0, the dollar-mark, and the further ornamentation found in the letters occurs in the punctuation-marks not enumerated and in the pound-sterling mark, as well as in those 30 cited.

I claim as new—

The design for a font of printing-type, as shown and described.

HENRY BREHMER.

W. V. H. HICKS,
A. SIDNEY DOANE.
